UNITED STATES PATENT OFFICE.

THOMAS N. CAHILL AND JAMES T. TURNER, OF ROUND MOUNTAIN, NEVADA.

NON-REFILLABLE BOTTLE.

1,287,873.

Specification of Letters Patent. Patented Dec. 17, 1918.

Application filed February 3, 1917. Serial No. 146,411.

To all whom it may concern:

Be it known that we, THOMAS N. CAHILL and JAMES T. TURNER, citizens of the United States, and residents of Round Mountain, 5 in the county of Nye and State of Nevada, have invented a certain new and useful Improvement in Non-Refillable Bottles, of which the following is a specification.

The present invention relates to bottles, 10 or other receptacles having cylindrical outlet portions, and has more particular reference to an attachment for bottles or receptacles of this nature to prevent refilling of the same, after the contents have been removed therefrom.

It is an object of the present invention to provide a non-refillable attachment for bottles and the like which requires but relatively slight modifications in the formation 20 of the bottle neck.

The invention further aims at the provision of an attachment of this character which comprises relatively few parts which may be easily and economically manufactured and assembled, and which when in place will not interfere with the pouring out of the contents of the bottle, and which will positively prevent the refilling of the bottle.

30 A still further object of the present invention is to provide an attachment in the form of a plug adapted to be fitted into the neck of a bottle, and to provide a novel securing means for holding the plug positively in the bottle and preventing the removal thereof when once in position.

Various other objects and advantages of this invention, as well as the above, will be brought out more particularly in the following specific description of the present preferred embodiment, the same being illustrated in the accompanying drawings wherein:

Figure 1 is a longitudinal section of the 45 upper end of a bottle in upright position, showing a non-refillable attachment in elevation applied thereto and constructed according to the present invention.

Fig. 2 is a longitudinal section taken substantially centrally through the plug or attachment, showing the inner and outer end 50 passages.

Fig. 3 is a transverse section taken on the line 3—3 of Fig. 1, showing the relation of 55 the lateral ports of the inner and outer end

passages and the radial partitions to prevent direct communication between the passages.

Fig. 4 is a transverse section taken on the line 4—4 of Fig. 1, showing the solid central portion or web of the plug for separating the opposite end passages thereof.

Fig. 5 is a transverse section on the line 5—5 of Fig. 1, taken through the lower passage of the valve chamber.

Fig. 6 is a longitudinal section similar to Fig. 1, showing the bottle overturned to pour out the contents therefrom.

Fig. 7 is a transverse section taken on the line 7—7 of Fig. 1, showing the locking ring in place for holding the plug in the bottle neck.

Fig. 8 is a longitudinal section through the upper end of a bottle in upright position, showing the non-refillable attachment applied to a bottle neck of slightly different form, and wherein a cork or stopper may be directly applied to the insertible plug.

Fig. 9 is a view similar to Fig. 1, showing a modified form of retaining means for the plug.

Fig. 10 is a transverse section taken on the line 10—10 of Fig. 9, showing the modified form of retaining means for the plug.

Fig. 11 is a longitudinal section similar to Fig. 8, showing a further modified form of retaining means for the plug.

Referring to these drawings, wherein like parts are designated by similar characters of reference throughout the several views, A designates a bottle of usual form provided with a neck B provided near its upper end with an upwardly facing shoulder C upon which is seated a packing ring D, of cork or the like, which is fitted in the upper end of the neck B and adapted to bind about the depending portion of a glass stopper or plug E, in the usual manner.

The neck B of the bottle or receptacle is provided at its inner end with an interior annular shoulder 15 upon which is seated a packing ring 16, of cork or the like, which is fitted in a rabbet 17 formed annularly and exteriorly in the lower end of an elongated plug 18. The plug 18 is of cylindrical or other form adapted to fit snugly in the neck B of the bottle, and may be made of glass or other suitably and economically handled material. The plug 18 is inserted inwardly from the outer end of the bottle neck B and is limited by the shoulder 15.

The plug 18 is held in place by means of an 5
expansible locking ring 19 which is seated in an annular groove 20 formed in the outer 10
surface of the plug 18 adjacent to its outer 15
extremity. The bottle neck B is provided, at
a point a short distance inwardly from the
shoulder C, with an annular groove or channel 21 into which the locking ring 19 is
adapted to expand for firmly locking and
securing the plug 18 within the neck of the
bottle.

The plug 18 is provided with an outer end 15
passage 22 which extends longitudinally in
the outer end of the plug and opens through
the end of the same. A second longitudinally
extending passage 23 is formed in the 20
inner end of the plug and opens through
the same into the bottle A, the passage 23
being of greater diameter than the passage
22 and constituting a valve chamber. The
inner end of the chamber 23 is constricted
or reduced in diameter to provide a valve
seat 24 upon which a valve 25 is adapted
to seat, the valve 25 being formed of glass
25 and being preferably of cylindrical or ball
construction. The adjacent ends of the pas-
sages 22 and 23, at the intermediate portion
of the plug 18, are closed from intercommu-
nication with each other by means of a web
30 26 which constitutes the intermediate por-
tion of the plug. The passages, however,
lead into laterally extending ports or exits
27 and 28, for the passages 22 and 23 re-
spectively. From Fig. 3, particularly, it
35 will be noted that the ports 27 and 28 open
through substantially the same side of the
plug 18 and are offset peripherally but a
slight distance one from the other. The
ports 27 and 28 are closed from direct com-
40 munication with each other by means of a
radially extending web or partition 29. In
Fig. 1, the ports 27 and 28 are shown as
in slightly overlapping relation, and the
partition 29 which separates these ports ex-
45 tends obliquely to the longitudinal axis of
the plug 18 from one side of the port 28 out-
wardly to the opposite side of the port 27.
The plug 18 is provided with a substantially
50 annular groove 30 into which the ports 27
and 28 open, and which is interrupted by
the partition 29. The inner wall of the
bottle neck B is adapted to close the outer
55 side of the channel or groove 30 and to
provide, in conjunction with the partition
29, a substantially annular passage leading
from the lower or inner port 28 to the outer
or upper port 27.

The port 28 is made relatively large for
the introduction and removal of the ball
60 valve 25, and a detachable retaining pin
31 is secured transversely through the plug
18 across the port 28 to prevent outward
movement of the ball valve 25 sufficiently
to block the port 28. When the bottle A
65 with the plug therein is inverted, as shown

in Fig. 6, the ball valve 25 passes outwardly
in the chamber 23 and bears against the
pin 31, the latter holding the valve from
blocking the port 28.

In Fig. 8 of the drawings, a bottle A is 70
shown provided with a neck B' which is
of slightly different form, the shoulder C
and the packing ring D being eliminated.
With this form of neck, the annular groove
75 or channel 21 is formed adjacent to the top
edge of the neck B' and the plug 18 when
in position has its outer end flush with the
outer end of the bottle neck. The stopper
F employed is preferably of cork, or other
80 yielding material which permits of the in-
sertion of the stopper F directly in the outer
end passage 22 of the plug to close the same
and seal the contents of the bottle. In
this form of the invention the plug 18 must
be forced against the washer 16 to compress
85 it and seal the plug in the neck B'.

In Figs. 9 and 10, there is shown a slight
modification in the plug and the securing
means therefor. The plug 18^a is of sub-
stantially the same form as disclosed above,
90 with the exception that the upper end there-
of is provided with a smooth uninterrupted
peripheral surface. The bottle neck B^a is
provided with a smooth inner surface, has
the shoulder 15 at its inner end to support
95 the plug 18^a, and is provided near its outer
end with the shoulder C and the packing
ring D.

A cap 32 fits over the outer end of the
bottle neck B^a and is provided in its in-
100 ner wall with an annular channel or groove
20^a within which is fitted a contracted lock-
ing ring 19^a adapted to spring into an an-
nular groove 21^a formed in the outer sur-
face of the bottle neck B^a. The cap 32
105 is provided with a central opening 33
through which the stopper may be inserted
when forced into the bottle neck to seal the
contents thereof. The inner marginal edge
110 of the cap 32 overlaps the packing ring D
and prevents the removal thereof, the pack-
ing ring D being seated upon the shoulder
C and engaging against the outer end of
the plug 18^a to hold the same firmly in the
bottle neck B^a, and from displacement from
115 the shoulder 15.

It will be noted that should stopper E
be removed, and the cork packing ring D
be cut or otherwise mutilated and removed,
120 the opening 33 in cap 32 is of such size that
the plug 18^a cannot be removed, thus pre-
venting the refilling of the bottle.

In Fig. 11, there is shown a slightly fur-
ther modified form of the securing or at-
taching means for the plug. In this in-
125 stance, the bottle A is provided with a neck
B^b, into which the plug 18^a is inserted, and
wherein the shoulder C and packing ring
D are omitted. In this instance, the plug
18^a has its outer end flush with the outer
130

end of the bottle neck B^a, and the cap 32 is provided therein with a disk 34 of any suitable material, such as cork to seal plug 18, and to provide a cushion for the cap 32, adapted to seat upon the outer end of the bottle neck and the plug, and to securely hold the plug from displacement from the bottle neck. The disk 34 is suitably apertured to receive the stopper F therethrough for engagement directly in the outer passage 22 of the plug. It will be noted that the inner marginal edge of the cap 32 is substantially flush with the inner marginal edge of the disk 34, and that both of the same lap over upon the end of the plug 18^a to firmly hold the plug in position.

From the above, it will be readily understood that the plug attachment and the securing means therefor, of this invention, may be readily applied to bottle necks of usual construction with but slight additions or variations to the same, and that the usual stoppers, caps and the like for sealing the bottles may be employed.

In operation, when the stopper E is removed and the bottle is overturned or inverted as shown in Fig. 6, the valve 25 falls outwardly by gravity away from the valve seat 24 and rests upon the pin 31. While in this position, the contents of the bottle is permitted to flow outwardly through the inner passage 23, port 28 past the valve 25, around the plug 18 in the groove 30, and outwardly through the port 27 and outer passage 22.

When the bottle is turned into upright position for filling, as shown in Fig. 1, any liquid poured downwardly into the neck B of the bottle will pass through the opening 22, port 27, and into the groove 30. The fluid will also pass through the port 28 into the lower passage 23, but will be held therein and from further passage through the bottle neck by the valve 25 which is seated on the valve seat 24. As the valve 25 is of glass, or other relatively heavy ma-

terial, it will not float in the liquid and will provide an effectual seal to prevent the refilling of the bottle A. The substantially annular groove 30 and the partition 29 effectively prevent the introduction of a wire or other device for unseating the valve 25.

It is of course understood that various changes and modifications may be made in the details of construction of the above-described part of this device without departing from the spirit of the invention, and being restricted only by the scope of the following claim.

We claim:

In a non-refillable bottle, the combination with a bottle and neck therefor having an annular shoulder formed near the inner end of the neck, of a plug inserted in the said neck and having its inner lower end reduced in diameter, a cork collar mounted about said reduced end and resting upon said shoulder, said plug provided with an annular peripheral groove intermediate its ends, the reduced end of said plug provided with a longitudinal central bore opening out into a valve chamber in said plug and below said peripheral groove, a ball valve positioned in said valve chamber, said plug having an angular opening therein communicating with said valve chamber and peripheral groove, the upper end of said plug provided with a central longitudinal bore having its inner end curving outwardly and communicating with said peripheral groove to one side of the communication between the groove and said angular opening, and a partition traversing the groove between said angular opening and the lower outwardly curving end of said bore, and a pin extending diagonally through said valve seat near said angular opening to prevent passage of said ball valve through the angular opening.

THOMAS N. CAHILL.
JAMES T. TURNER.
